DESIGN FOR A DEVICE FOR PREVENTING SEWAGE BACKFLOW INTO A LIQUID CON- TAINER OF A WATER SUPPLY SYSTEM

Edward W. N. Boosey, Detroit, Mich.

Application July 28, 1941, Serial No. 102,522

Term of patent 14 years

To all whom it may concern:

Be it known that I, Edward W. N. Boosey, a citizen of the United States, residing at Detroit, county of Wayne, and State of Michigan, have invented a new, original, and ornamental Design for a Device for Preventing Sewage Backflow into a Liquid Container of a Water Supply System, of which the following is a specification, reference being had to the accompanying drawing forming a part thereof.

The figure is a perspective view of a device for preventing sewage backflow into a liquid container of a water supply system embodying my new design.

I claim:

The ornamental design for a device for preventing sewage backflow into a liquid container of a water supply system, as shown.

EDWARD W. N. BOOSEY.
